Mark C. Fischer.

UNITED STATES PATENT OFFICE.

RICHARD MAX EATON, OF NIAGARA FALLS, NEW YORK.

DESIGN FOR AN ADAPTER-HEAD FOR FLASH-LIGHTS.

55,253.

Specification for Design.

Patented May 25, 1920.

Application filed March 18, 1920. Serial No. 366,987. Term of patent 7 years.

To all whom it may concern:

Be it known that I, RICHARD MAX EATON, a citizen of the United States, residing at Niagara Falls, in the county of Niagara and State of New York, have invented a new, original, and ornamental Design for an Adapter-Head for Flash-Lights, of which the following is a specification, reference being had to the accompanying drawing, forming a part thereof.

In the drawing, the figure represents a side elevation.

I claim:

The ornamental design for an adapter head for flash lights, as shown.

RICHARD MAX EATON.

Witnesses:

CARL S. WHISTLER,
THOMAS BRENNEN.
